UNITED STATES PATENT OFFICE.

LAFAYETTE HUNTOON, OF NATICK, MASSACHUSETTS, ASSIGNOR TO ELWIN C. HUNTOON, OF SAME PLACE.

BOILER FOR HEATING APPARATUS.

SPECIFICATION forming part of Letters Patent No. 366,629, dated July 12, 1887.

Application filed May 20, 1887. Serial No. 238,847. (No model.)

To all whom it may concern:

Be it known that I, LAFAYETTE HUNTOON, of Natick, in the county of Middlesex and State of Massachusetts, have invented certain new and useful Improvements in Boilers for Hot-Water Heating Apparatus, of which the following is a specification.

This invention has for its object to economize fuel in hot-water heating apparatus; and to this end it consists, mainly, in a boiler formed to surround the fire-box of the furnace, and also to extend over the same in the form of a dome.

The invention also consists in the combination, with a boiler of the form above indicated, of a casing or jacket surrounding and extending over the top of the same, and forming a chamber for the smoke and products of combustion, all of which I will now proceed to describe and claim.

Of the accompanying drawings, forming a part of this specification, Figure 1 represents a perspective view of my improved boiler. Fig. 2 represents a vertical section of the same.

Fig. 3 represents a section on line *y y*, Fig. 2. The same letters of reference indicate the same parts in all the figures.

In the drawings, *a* represents the fire-box, *b* the grate, and *c* the water-jacket. Said jacket is formed to surround the fire-box, as shown in Fig. 3, and also to extend across the top of said box, as shown in Fig. 2, the jacket having a dome, 2, conducting the water over the fire-box.

d represents the casing surrounding the water-jacket, and arranged so that a space, *s*, exists entirely surrounding the water-jacket and extending over the top or dome thereof. In said casing, near its upper portion, is a door, *e*, with which coincides an opening, *f*, extending through the water-jacket, for the introduction of fuel into the fire-box and for the escape of smoke and products of combustion into the space or smoke-chamber *s*; or, if preferred, a separate opening, *f'*, may be provided from the fire-box to the smoke-chamber through the dome, which opening may have a valve or damper, *g*, arranged to be opened when the fuel-door *e* is opened, to prevent the escape of smoke and gases into the apartment. Said

damper may be closed at other times to cause the products of combustion to pass to the smoke-chamber through the opening *f*, and thus act on a greater extent of the external surface of the water-jacket and its dome than if they passed out through the top opening, *f'*, the side opening, *f*, being at the opposite side of the jacket from the flue *i*, through which the products of combustion leave the casing *d*, so that the products of combustion emerging from the side opening, *f*, have to pass entirely around the jacket *c*. The flue *i* is located at the lower portion of the casing, as shown in Fig. 2.

I prefer to provide a draft-opening at *j* in the rear wall of the ash-pit *k*, or in the side of the casing *d* opposite to that in which the door *e* is formed, so that the air will pass across the fire-box before escaping at the opening *f*, as indicated by the arrows in Fig. 2. The fuel is thus more fully exposed to the draft than it would be if the air entered at the front side of the ash-pit.

It will be seen that by carrying the water-jacket over the fire-box I obtain a large extent of surface exposed to the heat from the fire, and thus economize fuel.

m m represent the pipes through which water enters the lower portion of the water-jacket, and *n n* represent the pipes through which the heated water passes from the jacket to the radiating-coils.

I claim—

1. In a water-heating apparatus, the combination of the fire-box, the water-jacket extending down to the grate and over the top of the fire-box, as shown, and provided with a fuel-receiving opening, *f*, and the casing surrounding and extending over said jacket, and having a door, *e*, coinciding with the opening *f*, as set forth.

2. The combination of the fire-box, the water-jacket surrounding said box and having a dome covering the same, and an opening, *f*, in one side below said dome, the casing having the door *e* coinciding with the opening *f*, and the escape-flue *i* at the opposite side from the door *e*, as set forth.

3. The combination of the fire-box, the domed water-jacket having the valved opening *f'* in its dome, and the side opening, *f*, and the cas-

ing *d*, having the door *e*, coinciding with the side opening, *f*, and the escape-flue *i* at the opposite side from the door *e*, as set forth.

4. The combination of the fire-box, the domed water-jacket having the side opening, *f*, the casing *d*, having the door *e*, coinciding with the opening *f*, and the ash-pit having the draft-opening *j* at the opposite side from the opening *f*, and door *e*, whereby a cross-draft is caused, as set forth.

In testimony whereof I have signed my name to this specification, in the presence of two subscribing witnesses, this 14th day of May, A. D. 1887.

LAFAYETTE HUNTOON.
